CLAIM

The ornamental design for a remote control device, as shown and described.

DESCRIPTION

FIG. 1 is a top plan view of a first embodiment of a remote control device showing our design;

FIG. 2 is a right side view of the first embodiment of a remote control device showing our design;

FIG. 3 is bottom plan view of the first embodiment of a remote control device showing our design;

FIG. 4 is a perspective view of the first embodiment of a remote control device showing our design;

FIG. 5 is a top plan view of a second embodiment of a remote control device showing our new design;

FIG. 6 is a right side view of the second embodiment of a remote control device showing our design;

FIG. 7 is a bottom plan view of the second embodiment of a remote control device showing our design; and,

FIG. 8 is a perspective view of the second embodiment of a remote control device showing our design.

The broken line showing of control buttons of FIGS. 1, 4, 5, and 8 are environmental only and form no part of the claimed design. The broken line showing of detail in FIGS. 3 and 7 are environmental only and form no part of the claimed design.
